WRAPPING AND PACKAGING MACHINE

Edward F. Ness, Toledo, Ohio, assignor to Morris Packaging Equipment Company, Toledo, Ohio, a corporation of Ohio

Application July 16, 1935, Serial No. 31,630

16 Claims.

(Cl. 93—2)

This invention relates to machines for wrapping individual prints or bars of butter, oleomargarine, and the like, with flexible sheet material, thereafter arranging the wrapped bars in a predetermined manner and packaging them in cartons, and an object is to produce a new and improved machine of the above character, which is relatively simple in construction and automatic in operation and has the novel features of arrangement hereinafter described.

Other objects of the invention are to produce a simple and efficient conveying mechanism by which the prints are individually advanced to the wrapping mechanism, to enable inspection and replacement of damaged prints or bars; to produce a new and improved sheet feeding and severing device by which the sheet material is printed and fed continuously to position of use, the printing being predetermined with respect to the severing operation so that each severed segment contains printed matter in the desired position, the sheet feeding mechanism operating continuously in such manner as to avoid buckling; to produce an improved wrapping mechanism which militates against damage to the prints or bars during the wrapping operation and insures that the sheet material will be retained folded during subsequent operations; to improve the carton feeding mechanism in such manner that any damage to a carton blank during the feeding will not injure the carton or render the folded carton unsightly; to provide a new and improved device for stacking the prints or bars in a relatively simple manner and so that no damage to the bars results; and to provide simple and efficient carton closing mechanism which enables the carton to be closed quickly and insures against damage to the contents during such operation.

Further objects and advantages of the invention will hereinafter appear, and, for purposes of illustration but not of limitation, an embodiment of the invention is shown in the accompanying drawings, in which:

Figure 1 is a vertical sectional elevation partly diagrammatic of a machine for wrapping prints or bars of butter, oleomargarine, or the like, stacking the wrapped bars in a predetermined manner and then packaging the stack in a carton;

Figure 2 is a top plan view of the machine shown in Figure 1 with the carton feed removed;

Figure 3 is an enlarged vertical section diagrammatically showing the primary print feed and the conveyor for conveying the individual prints to a vertically moving ram;

Figure 4 is a detailed view showing the drive mechanism for the print conveyor;

Figure 5 is a perspective view partly in section of the folding plates for folding the ends of the sheet material against the prints or bars;

Figure 6 is a vertical sectional view showing the housing through which the bars or prints are moved vertically partially to wrap the sheet material thereabout;

Figure 7 is a fragmentary view of one of the end folding plates and a portion of the housing through which the individual bars are moved to effect folding of the sheet material;

Figure 8 is an elevation partly in section showing diagrammatically the apparatus for folding the sheet material about the individual prints or bars;

Figure 9 is a sectional elevation showing the arm for folding the rear flap of the parchment or sheet material against the underside of the print or bar;

Figures 10, 11, 12, 13, and 14 are perspective views of an end portion of a print or bar showing successively the steps of folding the sheet material thereabout;

Figures 15 and 16 are side elevations partly in section showing the final folding operations of the sheet material about the bar, Figure 16 showing the manner of moistening the overlapping flaps for retaining them in position;

Figure 17 is a diagrammatic elevation partly in section showing the mechanism for stacking the wrapped prints or bars and advancing the stack into engagement with the carton to the carton elevator and the pusher for advancing the stack partially enclosed by the carton;

Figures 18, 19 and 20 are side elevations partly in section showing diagrammatically the folding of the panels against the sides of the stack;

Figure 21 is a top plan view showing the mechanism for folding the end flaps of the carton against the stack;

Figure 22 is a sectional elevation showing the devices for breaking the lips on the end tucks;

Figure 23 is a fragmentary detail elevation showing the manner of breaking the lip on one end tuck;

Figure 24 is a fragmentary detail elevation showing the manner of breaking the lip on the opposite end tuck;

Figure 25 is a vertical sectional elevation showing the mechanism for inserting the lips of opposite end tucks inside the carton looking toward the front end of the machine;

Figure 26 is a view in elevation showing the

gripper for bowing the uppermost panel of the carton for facilitating and insuring the insertion of the adjacent lip inside the carton;

Figure 27 is a longitudinal sectional elevation showing the shelf for raising the stack and carton, for folding the side panels, and also showing the devices for folding the end flaps; and

Figure 28 is a plan view of a carton blank.

The illustrated embodiment of this invention 10 comprises a machine on which are placed individual bars or prints of butter, oleomargarine, or other similar semi-plastic materials. The operator ordinarily takes these prints from a printing machine, which forms the bars of the desired sizes, and places them on a conveyer A, which advances them to another conveyor B, which moves at a higher rate of speed than the primary feed, spacing them an appropriate distance apart. From the conveyor B the individual prints are moved vertically through a wrapping device C which operates to wrap each print with a sheet of relatively thin flexible material such as parchment paper. The wrapped prints are then advanced to a stacker D, which 15 arranges four prints in a symmetrical stack. A carton feeding device E delivers a carton blank in upright position into the path of movement of the stack of wrapped prints. During the further advancing movement of the stack, the carton is wrapped about it by the carton folding mechanism F, whereupon the package is discharged from the machine.

Referring particularly to the drawings, it will be understood that only so much of the operating mechanism is shown to enable those skilled in this art fully and adequately to understand the nature and operation of the invention. Effort has been made to omit unnecessary detailed disclosure of parts which tend only to obscure the real invention, but, on the contrary, as many of the parts have been shown diagrammatically to facilitate understanding of the structure and operation of the machine as possible. The primary feed A, to which the individual bars 10 of butter, oleomargarine, or the like, preferably of one-quarter pound size, are delivered, 20 comprises a movable table 11 reciprocating between stationary guides 11^a on which opposite ends of the prints 10 are disposed. A step-by-step motion is imparted to the table 11 by a rocker arm 12 having a roller 13 at its upper end operating in a vertical guide 14. This serves to reciprocate the table 11 longitudinally. At predetermined points in the swinging movement of the arm 12, the table is raised or lowered; raised during the advancing movement and lowered during the retracting movement. This is accomplished by an arm 15, which is pivotally connected at its lower end to a horizontal arm 16, which is movable with a horizontally swinging arm 17. The upper end of the arm 15 has a cam surface 18 and carries a roller 19, which is adapted to move vertically in a guide 20. Connected to the lower end of the rocker arm 12 is a rod 21 and connected to the lower end of the arm 17 is a rod 22, the opposite end of which may be driven in any suitable manner to effect the desired movement. It should be noted that the arm 17 is fixed to a shaft 23, to which is fixed a vertical arm 24, from which extends a link 25 for operating an arm similar to the arm 15 adjacent the forward end of the table, a link 26 extending from the upper portion of the arm 15 cooperating with the link 25 and effecting the desired motion.

The prints 10 are thus advanced step-by-step toward an elevator or pusher 27, passing beneath a guide 28 disposed above a stationary platform 29, the foremost print being moved beyond the rear edge of the platform, whereupon the elevator 27 engages its upper surface and pushes it downwardly to the chain conveyor B. A bell crank 30 is driven in any suitable manner by a rod 31 and engages the lower end of the elevator 27 to impart the vertical reciprocatory movement thereto.

The chain conveyor comprises a pair of chains 32 spaced laterally from each other. Disposed on the chains are shelves or platforms 33 secured at one end to a stop member 34. Adjacent the opposite end of the shelf 33 is another stop member 35. The elevator 27 lowers the individual prints 10 so that opposite end portions thereof rest upon the platforms 33. The lugs 34 and 35 afford a safety measure so that the operator replacing a bad print will not place it on the chain conveyor incorrectly. It will be understood that the prints must be placed properly upon the chain conveyor so that the ram, which raises them, as will hereinafter appear, operates in timed relation to the chain, and if the prints are not properly disposed on the conveyor, they will not be engaged by the ram.

The chain conveyors are trained over sprockets disposed at opposite ends in the usual manner, and, as shown in Figure 4, the shaft 36 on which the rear sprocket is mounted, has a small gear 37 meshing with a large gear 38 to which is fixed a smaller sprocket 39 to receive a chain drive 40 driven in any suitable manner so that the chain conveyor B moves at three times the rate of speed of the primary feed A. It will be understood that by spacing the prints in the manner effected by the chain conveyor, each print may be inspected by an operator, and if one print is damaged, or otherwise unsuitable for wrapping, it can be replaced by another one.

The prints are individually lifted from the chain conveyor B by a vertically movable ram 41, which, as shown in Figure 8, moves upwardly between the chains 32 and engages the under surface of the print, forcing the same upwardly through the wrapping steps, as will hereinafter appear. Vertical movement is imparted to the ram 41 by a rocker arm 42, the forward end of which is connected by a link 43 to the lower end of the ram, the opposite end of the rocker arm being connected to an eccentric strap 44 engaging an eccentric cam 44^a thereby imparting vertical reciprocatory movements to the ram 41 from the rocking movements of the arm 42.

Relatively thin flexible sheet material, such as relatively thin parchment paper, is delivered into the path of vertical movement of the print. In this instance, the sheet material 45 for wrapping the individual prints is fed from a roll 45^a, passes around a guide roll 46 between printing rolls 47 and 48, over guide rolls 49 and 50 to a pair of driven draw rolls 51 and 51^a and thence to a pair of grip rolls 52, a perforating roll 53 and its cooperating roll 54 being disposed between the draw rolls 51 and grip rolls 52.

The printing roll 48 has diametrically opposed type segments 55 and relieved portions 56, and the roll 47 has a flexible or resilient covering 57 therefor. Ink is supplied to the type segments 55 through rolls 58 and a feeder roll 59, which may be manually or automatically rocked into and out of engagement with a roll 60 operating in an ink

bath 81 for delivering the desired amount of ink to the type segments.

The grip rolls 52 are driven at a higher peripheral speed than the draw rolls 51 in order to maintain the sheet taut at the time of perforating. The perforating roll 53, which carries a row of perforating teeth 53a, operates at a greater peripheral speed than either of the pairs of draw rolls 51 and 52. The teeth 53a perforate the sheet material 45 between the pairs of draw rolls, whereupon the grip rolls 52 abruptly tear the sheet segment 62 along the line of perforations and feed it forwardly into the path of movement of the bar or print. One advantage of this operation is that since the sheet is maintained taut at the time of perforating, no buckling or misalignment of the sheet material takes place.

Heretofore the sheet material has been printed separately and then formed into rolls, but this 20 has been objectionable because oftentimes severance will not take place at the proper point, and some of the printed matter will be omitted from the sheet enclosing an individual print. This objection is eliminated by the above described arrangement in which printing and severing are accomplished successively without interruption. The operation of the severing roll 53 is timed with respect to the operation of the printing rolls to insure that severance will take place 30 between the printing. This insures that each print is wrapped with a sheet containing the desired printing matter.

The segment 62 severed from the strip of sheet material 45, is advanced by the grip rolls 52 to a 35 pair of laterally spaced supporting fingers 63 (Figure 8) so that as the ram 41 moves upwardly it moves the respective print 10 into engagement with the underside of the sheet material 62 and then moves the same into a housing 64, the width 40 of which is slightly greater than the width of the print 10. It will be noted that the parchment paper of the segment 62 projects beyond the opposite ends of the print 10, and during the upward movement of the ram 41 the opposite 45 sides of the segments are first folded downwardly, as indicated in Figure 10. As the ram 41 continues its upward movement, end folding plates 65 disposed on opposite sides of the housing 64 operate successively to fold the upper panel downwardly against the ends, leaving the sides extending 50 outwardly as indicated in Figure 11, and thereafter successively folding one flap inwardly and then the other flap over the first flap, as shown in Figures 12 and 13. The above described 55 sheet folding operations are old in the art, and detailed description of the folding plates to accomplish this purpose is not considered necessary.

It should be noted that the front plate 66 of the housing is movable slightly forwardly to compensate for irregularities in the size of the prints; coil springs 67 being disposed between arms 68 and the plate 66 yieldingly to urge the plate into engagement with the print so as to insure proper folding operation but not to interfere with the vertical movement of the print.

After the ram 41 has moved the print to the upper portion of the housing 64, it retracts, whereupon folding fingers 69 disposed on opposite sides of the housing 64 are moved inwardly beneath the print 10 to effect the bottom folds at opposite ends of the print, as shown in Figure 14, and to support it in its raised position. Arms 70 operate in any suitable manner in timed relation to the movement of the ram 41 and actuate the fingers 69 to and from operative position.

As indicated in Figure 14, the front and rear sides of the wrapping sheet project downwardly beyond the finger 68, and in order to fold the front portion of the sheet against the underside of the print 10 a folding arm 70a (Figure 9) is 5 pivoted at its lower end at 71, and has a finger 72 pivoted at its outer end and extending at substantially right angles to the arm. A spring 73 urges the finger 72 against a roller 74 mounted on the plate 66 of the housing 64. It will be noted that the under surface 75 of the finger 72 tapers 10 outwardly from the outer end.

In operation, after the fingers 69 have moved inwardly to support the print, the arm 70 is actuated in a counterclockwise direction (Figure 15 9), and concomitantly the fingers 69 are retracted. Inasmuch as the spring 73 keeps the tapered surface 75 in contact with the roller 74, it will be seen that the end portion of the finger 72 first engages the sheet material beneath the 20 print and folds the same rearwardly and then gradually moves upwardly into engagement with the underside of the print. This operation is of advantage in that it eliminates any liability of tearing the parchment paper or of damaging the 25 print, thereby insuring the desired fold against the underside of the print at each operation in spite of any irregularities in the formation of the print.

As above explained, the fingers 69 are retracted 30 from the print 10, leaving the finger 72 as the support for the print. Thereupon a ram 76, driven in any suitable manner in timed relation to the operation of the arm 70a, moves into engagement with the front side of the print and advances 35 the same to a shelf 77 having side guides 78. Formed in the shelf 77 is a row of relatively small holes 79, which communicate with a reservoir or container 80, to which a liquid, such as water under pressure, is delivered through a pipe 40 81, so that drops of liquid are forced through the openings 79 sufficient to moisten the bottom flaps of the sheet material enclosing the print 10. It will be understood that the ram 76 in advancing the print causes the rear flap abutting the adjacent 45 wall of the housing 64 and which is shown depending in Figure 15, to be folded upwardly against the folded front flap. By moistening, the flaps are adhered, retaining them together and insuring against unfolding during subsequent 50 operations. It will be apparent that upon reaching the shelf 77 the individual print 10 is entirely wrapped in the parchment paper.

The ram 76 again advances to move two wrapped prints upon a lower shelf 82 of the 55 stacker D, this stroke of the ram being greater than its first stroke. Thereupon the ram 76 retracts to advance the next succeeding print merely to the shelf 77, as above described. After two wrapped prints have been delivered to the 60 stacker D, the latter moves vertically downward to align the upper shelf 83 with the shelf 77 to enable two additional prints to be similarly advanced upon the stacker. Depending from the lower side of the stacker D is a slide 84, which 65 is connected by a link 85 to an actuating arm 86, which is driven in any suitable manner in timed relation to the reciprocatory movement of the ram 76.

After four wrapped prints have been delivered 70 to the stacker D, the same is moved upwardly, as shown by dotted lines in Figure 17. As shown in Figure 2, the shelf 83 is provided with laterally spaced supporting ledges so that the intermediate portions of the bars are free. This enables a ram 75

85 to engage the front wall of the stack and advance the four prints as a unit from the stacker upon a platform 86 and into engagement with a carton blank 87, which is disposed in the path 5 of the movement of the stack. The lower end of the carton blank is supported by a pair of laterally spaced bracket members 88.

As shown in Figure 28, the carton 87 is of the usual construction having integral side panels *a*, 10 *b*, *c* and *d*, and a half panel *e*. On opposite sides of the side panel *a* are end panels *f* and *g*, and on opposite sides of the side panel *c* are end panels *h* and *i*. On one side of the half panel *e* is an end flap *j*. An end tuck *k* is connected to 15 one side of the panel *b* and has a lip *l*, and connected to the side *d* on the opposite side is an end tuck *m* having a lip *n*. It will be understood that the above described carton blank, which is ordinarily coated with paraffin, is of well known 20 construction, and is customarily used for packaging prints of butter, oleomargarine, or the like.

The carton blanks are fed into the path of movement of the stack of wrapped prints or bars by a carton feeding mechanism E. A stack 25 of cartons 87 is supported on this mechanism in vertically inclined position by vertically disposed plates 89 at the lower feeding end and agitator plate 90 at the upper end. A vertically disposed side guide 91 is arranged in pairs on opposite 30 sides of the blanks (only one pair being shown on the drawings). Disposed beneath the stack is an arm 92 mounted on a rod 93 providing a bottom support for the stack.

Disposed at the rear end of the feeding mechanism E adjacent the lower end of the stack is a sector member 94 having a knife edge 95 engageable with the lower edge portion of the lowermost carton. Engageable with the outer surface of the segment 94 is a pair of rollers 96 40 having rubber-like covers, and arranged between the rollers 96 is a guide member 97. The segment 94 is mounted on a shaft 98, which is driven by a chain 99 in timed relation to the reciprocatory movement of the ram 85 so that a carton will have 45 been fed into the path of movement of the ram 85 when the latter advances.

Also mounted on the shaft 98 is an eccentric strap 100, which is pivotally connected at its upper end to a rod 101 guided by a sleeve 102 and 50 connected at its outer end to the agitator plates 90. As the segment 94 rotates, vibratory movement will be imparted to the plates 90 to militate against the cartons adhering to each other, thereby facilitating and insuring proper feeding 55 action.

In operation of the carton feeding mechanism E, it will be apparent that the knife edge 95 of the segment 94 engages the lowermost edge portion of the lowermost carton and moves it from 60 the stack and discharges it between vertically disposed guides 103 and 104, the upper portion of the carton resting between these guide members.

An important feature of the carton feeding mechanism E resides in the arrangement of the 65 cartons in stack formation. Contrary to usual practice, the half panel *e* of the cartons 87 is disposed in the lowermost position and is engaged by the knife blade 95 to draw the individual cartons from the stack. As will hereinafter appear, 70 the half panel *e* is folded inside the carton, and, consequently, any rupture or tearing which might take place during the withdrawal of individual cartons from the stack will not interfere with the desired appearance of the finished package. 75 Herefore the reverse has been true, and the feed-

ing mechanism has engaged one of the panels, which is disposed on the outside of the folded package, and, consequently, when such imperfections appear, it is necessary to discard the carton and repackage the prints. According to the 5 above arrangement, this difficulty is obviated, and any slight rupturing and breaking of the carton blank in the half panel, does not require discarding of the carton.

As above mentioned, the ram 85 advances the 10 pile or stack of wrapped prints from the stacker D on to the shelf or platform 86 and then into engagement with the vertically disposed carton blank 87, which is supported by the end tuck *m* supported on the stop or bracket 88. The bracket 15 on the opposite side (not shown) is engaged by the end tuck *k*. The stack and carton are then moved forwardly between the lower portion of the carton guide 104 and its subjacent guide 105, which operates to fold the carton in the manner 20 indicated in Figure 18, the carton panel *c* being in the rear of the stack, the panel *b* engaging the top of the stack, and the panel *d* the bottom of the stack. The ram 85 continues its advancing movement until the stack and carton are moved 25 upon an elevator platform 106, which is actuated by a pair of bent arms 107 and 108 carried by a stationary bracket 109. Connected to the arm 107 is an actuating rod 110, in this instance driven by a cam mounted on the shaft 111 engaging 30 a lever 112 on the lower end of the rod 110, the shaft 111 being driven from a shaft 113 by beveled gears 114. The cam and its lever 112 are so chosen as to operate in timed relation to the movement of the ram 85 so that after a carton 35 and stack have been delivered to the elevator 106, the same commences its upward movement.

After the stack and its carton have been moved upon the elevator 106, a half panel folding arm 115 swings upwardly engaging the underside of 40 the panel *e* and folds the same against the front of the stack. The half panel folder 115 is mounted on the same shaft on which the arm 108 pivots and has an actuating extension 116 connected to an operating rod 117 having a cam lever 118 in 45 the lower end engaging a cam mounted on the shaft 111.

After the half panel *e* has been folded the elevator 106 commences its upward movement, whereupon the panel *a* engages an extension of 50 the carton guide 104, causing the same to be folded downwardly in overlapping relation to the half panel *e*. The half panel folder 115 remains in position until the panel *a* is in such position as to prevent unfolding of the half panel *e*. 55

As the stack and its carton are advanced by the elevator 106 the lip *n* of the tuck *m* rides over a finger 119 mounted on the outer end of a rod 120 carried by the elevator 106, the rod 120 being fixed and providing a pivotal connection 60 for the rod 108. The finger 119 is curved at its outer edge and its front edge portion inclines downwardly, as indicated at 121 (Figure 27) in order to guide the lip *n* during its movement upon the elevator platform. The rod 120 projects beyond the opposite side of the elevator platform and has an upwardly extending finger 122, the upper edge of which is beveled at 123. The end tuck *k* is guided upon the beveled end 123 of the finger 122. It will be seen that the beveled end 70 123 terminates in a point 123a and engages the line between the end tuck *k* and its lip *l* at which folding is to be accomplished.

During the upward movement of the elevator platform 106 a downward and outwardly inclined 75

stop member 124 engages the end tuck *m* adjacent the lip *n*, as indicated in Figure 24, so that as the upward movement continues the finger 118 causes the lip *n* to be broken, folding the lip upwardly at substantially right angles to the end tuck *m*. When the elevator platform 106 reaches its uppermost position the upper portion of the finger 118 overlaps the stop member 124.

Concomitant with the breaking of the lip *n* the 10 lip *l* is broken by engagement with a downwardly and inwardly inclined stop member 125, causing the lip *l* to extend downwardly at substantially right angles to the end tuck *k*. To prevent the end tuck *k* from moving or bowing upwardly, a 15 downwardly and inwardly inclined stop member 126 engages the upper surface of the end tuck *k* in the region of the finger 122.

Further horizontal advancing movement of the 20 stack and its carton is effected by a pair of pusher members 127 (Figures 2 and 17) mounted on a horizontal rod 128, which is driven in any suitable manner in timed relation to the vertical movement of the elevator platform 106.

It will be seen that the pusher members 127 25 are substantially V-shaped and engage the front upper corner portions of the carton. Just prior to the advancing movement of the pusher members 127, end flap folding fingers 129 and 130 (Figure 21) disposed on opposite sides of the 30 carton, engage end flaps *f* and *g* respectively, and move the same inwardly against the opposite ends of the stack, as shown diagrammatically in Figure 21. Any suitable mechanism may be provided for operating the fingers 129 and 130 in timed 35 relation to the movement of the elevator platform 106, the operation of the folding fingers taking place just after the platform has reached its uppermost position. Thereafter the pusher members 127 advance the carton into engagement 40 with pairs of guide fingers 131 and 132 arranged in laterally spaced relation to engage the end flaps *h* and *i* respectively, so that as the carton is advanced the flaps *h* and *i* are thereupon folded inwardly against the folded end flaps *f* and *g* respectively. It will be noted that one pair of folding 45 fingers is arranged on opposite sides of the path of carton movement, the fingers of each pair being arranged in vertically spaced relation (Figure 27).

50 It will be understood that the elevator platform 106 remains in its upper position until the pusher members 127 have advanced the carton sufficiently so that the lip *n* of the end tuck *m* has moved forwardly sufficiently to engage a guide finger 133 spaced outwardly from the stop member 124, which cooperates with the finger 133 in holding the 55 lip *n* in the desired upright position. In a similar manner the lip *l* of the end tuck *k* is guided during its further advancing movement by the stop member 125 and a finger 134, which is spaced inwardly from the member 125, these two parts retaining the lip *l* therebetween in its downwardly disposed 60 position.

The pusher members 127 continue the advancing movement of the carton to the end tuck folding mechanism, which operates to force the lips *n* and *l* inside the carton, thereby completing the folding operation. In this position the end flaps *h* and *f* and *g* and *j* are held in folded position by spring fingers 135 (Figure 25), which are arranged horizontally and extend inwardly slightly into the path of movement of the carton after the carton has passed the folding fingers 131 and 132 sufficient to engage and hold 75

the end flaps from unfolding. These fingers are flexible and occupy a very small space.

The mechanism for folding the lips inside of the carton comprises a lower curved guide 136 to guide the lip *l*, the end tuck *k* being engaged 5 by an arm 137 pivoted at its upper end at 138. In opposed relation to the guide 136 is an upwardly curved guide 138, which guides the movement of the lip *n*, an arm 140 engaging the end tuck *m* for this purpose. The arm 140 is pivoted 10 at its lower end at 141. For actuating the arms 137 and 140, a rocker arm 142 is pivoted between its ends at 143, and a link 144 is pivoted to one end of the rocker arm 142, and at its upper end is pivoted to the arm 137 adjacent its pivot 138. 15 A link 145 is pivoted at one end to the arm 140 adjacent its pivot and at its opposite end to the rocker arm 142. For actuating the arm 142, a rod 146 is connected to one end of the rocker arm and has a strap 147 on its lower end engaging an 20 eccentric mounted on the shaft 111 (Figure 1).

To open the carton sufficiently to insure insertion of the lip *n* inside the carton, a pair of gripper members 148 mounted on a rod 149 are actuated by an arm 150, the outer end of which is 25 pivoted at 151. The arm 150 is actuated by a rod 152, which extends downwardly to engage a cam 153 for actuating it. Carried by the rod 149 between the gripper members 148 is an arm 154 having a leaf spring 155 on its underside. The 30 spring 155 engages the top panel *b* of the carton and presses the carton against its support. The gripper arms 148, as shown in Figure 26, incline downwardly and outwardly, so that upon engagement with the upper edges of the carton, they 35 operate to bow the top panel *b* upwardly. Almost immediately after the arm 150 has been actuated so that the gripper members engage the carton and the spring 155 is brought into contact with the upper panel, the rod 146 is actuated so that 40 simultaneously both arms 140 and 137, operating in opposite directions, swing the end tucks *m* and *k* inwardly toward the stack, the lips *n* and *l* riding over their respective guides being thereby forced inside the carton. It should be noted that 45 the guide 136 is notched to receive the carton so that the lower edge of the carton is below the guiding surface of the guide 136, thereby affording an unrestricted path for the movement of the lip *l* inside the carton.

50 Upon the next advancing movement of the pusher members 127, the succeeding carton pushes the carton which has already been entirely closed, to a downwardly inclined chute or guide-way 156 to discharge the finished package from 55 the machine.

It is to be understood that numerous changes in details of construction, operation and arrangement of parts may be effected without departing from the spirit of the invention, especially as defined in the appended claims.

What I claim as new and desire to secure by Letters Patent is:

1. In a machine of the class described having means for wrapping a substantially rectangular 65 bar of butter or the like with flexible sheet material whereby one side is closed by overlapping portions of the sheet material, a platform adapted to receive the wrapped bars with the overlapped portions lowermost, and means associated with said platform for moistening said overlapped portions of sheet material for militating against unfolding.

2. In a machine of the class described having mechanism for wrapping individual bars of but- 75

- ter, oleomargarine, or the like, with relatively flexible sheet material, and mechanism for stacking a predetermined number of wrapped bars in a symmetrical pile, and means intermediate said wrapping means and stacking means for moistening certain overlapped portions of sheet material on each bar for militating against unfolding thereof.
3. In a machine of the class described, carton folding mechanism comprising a support for the carton with its end tucks and lips extending outwardly therefrom in opposite directions, means for moving said support vertically, and means operable during the vertical movement of said support for breaking the lips at substantially right angles to the end tuck on opposite sides of the carton.
4. In a machine of the class described, a guide, a stacker having a pair of vertically spaced shelves movable at substantially right angles to said guide, and means adapted to advance a wrapped bar along said guide, retract and then advance another wrapped bar and the foremost bar onto one shelf of the stacker, the stacker thereupon moving vertically to position the other shelf for receiving other bars.
5. In an article wrapping and packaging machine, means to wrap an article with relatively flexible sheet material, said means including a folding arm, a cam surface on one side of said arm tapering outwardly from the outer end thereof, a roller with which said cam surface engages, yieldable means to hold said cam surface and roller in engagement, and means for bodily moving said arm relative to said roller thereby gradually to move same into engagement with an article for folding a portion of the sheet material.
6. A machine for wrapping and packaging bars of butter or the like comprising means for wrapping each bar with a relatively thin flexible sheet material, a support, a stacker in advance of said support, a pusher, means to operate the pusher to deliver one bar to the support, retract to engage another bar and then advance both bars to the stacker, means to move the stacker relative to the support to enable two additional bars to be delivered thereto to form a stack, said stacker moving means actuating same vertically away from said support, and separate means to discharge the stack of bars from the stacker when in such vertically disposed position.
7. A machine for wrapping and packaging bars of butter or the like comprising a support, a stacker in advance of said support, a pusher adapted to deliver one bar to the support, retract to engage another bar and then advance both bars to the stacker, means to actuate said stacker to lower same into position to receive two additional bars advanced by said pusher, said stacker actuating means elevating the stacker to a position above said support after said bars have been delivered thereto, and separate means for discharging the stack from the stacker when in elevated position.
8. In a machine of the class described, folding mechanism for a carton having opposed end flaps, one connected to one edge of the carton body and the other at a diagonally opposed edge, and each end flap having an end tuck for insertion into the carton body, said mechanism comprising a carton support, diagonally opposed curved end tuck guides, a bulging member opposed to said support and engageable with opposed side portions of the carton adjacent one guide for bowing the end of the carton, a presser member engageable with the carton for pressing same against the other guide and operable concomitantly with said bulging member, and means for folding the end flaps to cause the end tucks to move along said guides for insertion into the carton body.
9. In a machine of the class described, folding mechanism for a carton having opposed end flaps, one connected to one edge of the carton body and the other at a diagonally opposed edge, and each end flap having an end tuck for insertion into the carton body, said mechanism comprising a carton support, diagonally opposed curved end tuck guides, a bulging member opposed to said support and engageable with opposed side portions of the carton adjacent one guide for bowing the end of the carton, the other guide being notched to receive the end edge portion of the carton to facilitate insertion of the respective end tuck, a presser member resiliently engageable with the carton for pressing same against the other guide and operable concomitantly with said bulging member, and means for folding the end flaps to cause the end tucks to move along said guides for insertion into the carton body.
10. In a machine of the class described, folding mechanism for a carton having opposed end flaps, one connected to one edge of the carton body and the other at a diagonally opposed edge, and each end flap having an end tuck for insertion into the carton body, said mechanism comprising a carton support, diagonally opposed curved end tuck guides, means opposed to said support and engageable with opposed side portions of the carton adjacent one guide, means engageable with the carton for pressing same against the other guide and operable concomitantly with said side portion engaging means, and means for folding the end flaps to cause the end tucks to move along said guides for insertion into the carton body.
11. In a machine of the class described having means for wrapping a bar of butter or the like with relatively thin flexible sheet material, said wrapping mechanism including a folder for folding a portion of the sheet against the bar, said folder comprising an arm engageable with the sheet at a point away from the bar, means to advance said arm along the bar, and cam means acting against one side of said arm for gradually moving said arm closer to the bar thereby to fold the sheet thereagainst.
12. In a machine of the class described having means for wrapping a bar of butter or the like with relatively thin flexible sheet material, said wrapping mechanism including a folder for folding a portion of the sheet against the bar, said folder comprising an arm engageable with the sheet at a point away from the bar, means to advance said arm along the bar, a cam surface on said arm, and means cooperating with said surface for gradually moving said arm closer to the bar for folding the sheet thereagainst.
13. In a machine of the class described having means for wrapping a bar of butter or the like with relatively thin flexible sheet material, said wrapping mechanism including a folder for folding a portion of the sheet against the bar, said folder comprising an arm engageable with the sheet at a point away from the bar, means to advance said arm along the bar, a cam surface on the outer side of said arm, a stationary roller engageable by said cam surface, and spring means urging said arm against said roller, said

cam surface being designed gradually to move the arm flatly against the bar for folding the sheet thereagainst.

14. In a packaging machine, means for supporting a plurality of carton blanks in stack formation, means engaging a side flap of each carton for successively ejecting individual cartons from the stack, and a series of means for folding each carton blank operable to dispose said side flap on the inside of the folded carton whereby any damage to such flap will not be visible in the folded carton.

15. In a packaging machine, means for supporting a plurality of carton blanks in stack formation, each blank having a plurality of side panels and a flap connected to one of the side panels which, when the carton is folded, is disposed in the inside, a rotatable sector member adjacent the lower end of the stack, a knife member carried by said sector member and engageable with the lowermost carton blank for ejecting same from the stack, means in close

juxtaposition to said sector member for guiding each carton blank ejected by said knife, means to advance a stack of butter bars, means to support each carton blank with said flap disposed in lowermost position, and a series of means for subsequently folding the carton about the stack in such manner that said flap is disposed in the inside thereof.

16. The method of producing folded cartons, each carton being formed from a blank having a plurality of side panels and a flap connected to one side panel, said method consisting in arranging the carton blanks in stack formation, engaging successively such flap of each carton blank at one end of the stack and ejecting the individual blanks therefrom, and thereafter folding each blank so that such flap is disposed in the inside of the carton, whereby any damage to such flap will not be visible in the folded carton.

EDWARD F. NESS.
